[57] CLAIM

The ornamental design for a former board kit or similar article, as shown and described.

DESCRIPTION

FIG. 1 is a top plan view of a former board kit or similar article showing my new design;

FIG. 2 is a left side elevational view thereof, in open position, the right elevational view being a mirror image thereof;

FIG. 3 is a left side elevational view thereof in closed position, the right side elevational view being a side mirror image thereof;

FIG. 4 is a front elevational view thereof in open position;

FIG. 5 is a front elevational view thereof in closed position;

FIG. 6 is a bottom plan view thereof in open position;

FIG. 7 is a bottom plan view thereof in closed position;

FIG. 8 is a rear elevational view thereof in open position; and,

FIG. 9 is a perspective view thereof in open position.

FIG. 1.

FIG. 2.

FIG. 3.

FIG. 4.

FIG. 5.

FIG. 6.

FIG. 7.
